RADIOTELEMETRY TRANSMITTER FOR MONITORING HEART RATE

Roger Michael Glaser, 266-07 137th Ave.,
Laurelton, N.Y. 11413

Filed Dec. 28, 1970, Ser. No. 26,669

Term of patent 7 years

Int. Cl. D24—02

U.S. Cl. D83—1

FIG. 3

FIG.4

FIG.5

FIG.1

FIG.2

FIG.6

FIG.7

FIG. 1 is a front perspective view of a radiotelemetry transmitter for monitoring heart rate, showing my new design;

FIG. 2 is a rear perspective view thereof;

FIG. 3 is a front view thereof in orthographic projection;

FIG. 4 is a side view of FIG. 3;

FIG. 5 is a rear view of the FIG. 3; and

FIG. 6 is an elevation as seen in the direction of line 6-6 on FIG. 5.

FIG. 7 is an enlarged fragmentary section taken at line 7-7 in FIG. 5.

I claim:

The ornamental design for a radiotelemetry transmitter for monitoring heart rate, substantially as shown.
